UNITED STATES PATENT OFFICE.

JAMES LOGAN FITTS, OF MERCHANTVILLE, AND WILLIAM F. BILYEU, OF RIVERTON, NEW JERSEY, ASSIGNEES TO WARREN WEBSTER & COMPANY, OF CAMDEN, NEW JERSEY, A CORPORATION OF NEW JERSEY.

VENT FOR GRAVITY-FLOW METER AND HEATER APPARATUS.

1,371,554.

Specification of Letters Patent.

Patented Mar. 15, 1921.

Original application filed July 18, 1917, Serial No. 181,448. Divided and this application filed July 23, 1919. Serial No. 312,860.

To all whom it may concern:

Be it known that we, JAMES LOGAN FITTS, a citizen of the United States, residing at Merchantville, in the county of Camden, 5 State of New Jersey, and WILLIAM F. BILYEU, a citizen of the United States, residing at Riverton, county of Burlington, State of New Jersey, have invented a new and useful Vent for Gravity-Flow Meter and 10 Heater Apparatus, of which the following is a specification.

In the art of heating and measuring water, wherein a feed water heater is employed in conjunction with a weir or other 15 meter or measuring device, it is well known that conditions may arise to prevent the free entrance of steam into the feed water heater, which same conditions might prevent the free outflow of water from the 20 heater, and it is obviously desirable to provide for free inflow and outflow from both heater and meter at all times.

In the appliances of this general character, which are now on the market, a plain 25 equalizing pipe between the heater and the meter in conjunction with a vent pipe to the atmosphere has been employed, which is deficient, for the reason that this construction permits of a waste of steam through 30 this vent from the heater.

In our novel device, we employ the feature of the vacuum breaker, a check valve and a special gate valve, with a perforated disk, which permits a free discharge of air 35 without waste of steam and at the same time provides a means for automatically controlling a partial vacuum within the heater and the meter.

In addition to the use of a vent and 40 vacuum breaker of the character above described, we have successfully controlled the vent from the heater and meter apparatus by the use of a thermostatic valve which acts as a steam conserver, together with a check valve, which acts as a vacuum breaker 45 to prevent there being too great a vacuum within the heater and meter, since an excessive vacuum would result in holding a column of water in the heater and the meter and the piping to the pump to the detriment 50 of the pumping system.

We have also found from practical experience that in the combination of a feed

water heater and a meter, there are certain times when the steam supply is limited and is insufficient in volume to heat the 55 water to the highest temperature, the air which is expelled through the water accumulating in the top of the heating apparatus and rendering the device inoperative until this air has been removed by a pressure 60 of steam.

Also, to obviate the necessity of steam entering at a pressure to get rid of the air together with being able to use steam at pressure less than that of the atmosphere 65 by maintaining a partial vacuum in the feed water heater and meter, we employ a suitable suction creating or air drawing device in connection with our combined feed water heater and meter, which we have 70 found to possess advantageous features over the devices now in use.

To the above ends, our invention consists of the novel combination of a feed water heater, a meter, an air pipe communicating 75 with the interior of said heater and meter, and having a common air outlet branch leading to the atmosphere, a vacuum breaker, a check valve and a throttling valve 80 of novel construction located in said branch.

It further consists of a novel combination of a gravity flow meter, an air pipe communicating with the interior thereof, and having a branch leading to the atmosphere in which are located a vacuum breaker, a 85 check valve and a throttling valve.

To the above ends, our invention, which in its broad aspects is a division of our contemporaneously pending application filed July 18th, 1917, Serial No. 181,448, consists 90 of a novel construction of equalizing and venting device adapted for use in conjunction with a heater and a meter, the novel features of which will be hereinafter fully set forth and particularly pointed out in the 95 claims.

For the purpose of illustrating our invention, we have shown in the accompanying drawings forms thereof which are at present preferred by us, since the same 100 will give in practice satisfactory and reliable results, although it is to be understood that the various instrumentalities of which our invention consists can be variously arranged and organized and that our 105

invention is not limited to the precise arrangement and organization of these instrumentalities as herein shown and described.

Figure 1 represents a side elevation of a vent for gravity flow combined feed water heater and meter embodying our invention, a portion of a wall of the meter being broken away.

Fig. 2 represents on an enlarged scale a longitudinal sectional view of the vacuum breaker, check valve and special gate valve employed.

Similar numerals of reference indicate corresponding parts.

15 Referring to the drawings:—

1 designates a feed water heater of any suitable or conventional type, having a cold water inlet 2 and an inlet 3 for exhaust steam. 4 designates a gravity flow meter of 20 suitable construction, which is in communication with said feed water heater through the medium of the pipe 5 having the valve 6 therein, through which the heated water flows to the controlling valve 7, pipe 8, 25 branch 9 and valve 10 to said meter. 11 designates a gravity or sink pan or equivalent float mechanism, which is located in the discharge chamber 12 of the meter 4, said pan being suitably connected by the elements 14, 15 and 16 to the valve proper within the casing 7, whose detailed construction need not be described further, since the same, *per se*, forms no part of the present invention and is fully described in a 35 contemporaneously pending application filed by us.

17 designates a pipe leading from the interior of the heater and in communication with the pipe 18 leading from the interior 40 of the meter 4, through which is normally a free communication to the atmosphere. If pressure in excess of that required for heating water is present in the feed water heater 1, this will be relieved through the check 45 valve 18^x, whose internal construction will be apparent from Fig. 3, said valve 18^x comprising the casing having an inclined wall 19 therein, provided with a port 20 above which is located the valve proper 21, 50 which is supported in inclined position by the pivoted arm 22, it being understood that said valve 21 normally is seated and assumes the position seen in Fig. 3.

The check valve proper 21 is in the same 55 pipe line as the gate valve 23, which comprises the casing 24, the valve proper 25 having the port 26 therein, said valve being capable of being raised and lowered through the medium of the spindle 27 and hand 60 wheel 28.

It will be seen that the valve 23 while capable of being operated in the usual manner, cannot be used as a complete closure for the pipe 17 because of the small hole 65 drilled in the valve disk 25.

It will be apparent that by the provision of the valve 25 having the hole or port 26 therein, that when there is an excess of exhaust steam, and it is not desirable to discharge a considerable quantity to waste 70 through said valve, that the latter can be closed, in which event said port will serve as a restricted outlet for any air or other non-condensable gases which might otherwise accumulate in the heater and interfere 75 with its proper functioning.

It will be understood by those skilled in the art that there are times when it is the function of a feed water heater to operate under a partial vacuum during which times 80 the check valve 21 prevents atmospheric air from entering the heater, but it is undesirable to carry too high a vacuum in certain feed water heater constructions, for which reason we employ a vacuum breaker valve 29 85 seen in Fig. 2, which comprises the casing 30 having the valve seat 31 therein and the upwardly seating valve 32 carried by the spindle 33 having the nut, head or its equivalent 34 thereon, below which is the 90 spring 35, wherefrom it will be seen from Fig. 2 that the tension of the spring will normally hold said valve seated or so set that it will open upwardly to admit atmospheric air through the ports 36 in sufficient 95 quantity to reduce the vacuum within the desired limits.

The construction seen on an enlarged scale in Fig. 2 clearly shows the preferred manner of correlating the vacuum breaker 29, 100 the check valve casing 18^x containing the check valve 21, and the special gate valve 23 having a port 26 in the disk 25 thereof.

It will be understood from Fig. 1 that the pipes 17 and 18 are in communication with 105 the interior of both the feed water heater 1 and the meter 4 and that very advantageous results will be obtained by employing these pipes equipped with these vacuum controlling features seen particularly in Fig. 110 2 in combination with a feed water heater and a gravity flow meter.

It will now be apparent that we have devised a novel and useful construction of a vent for gravity flow meter and heater apparatus, which embodies the features of advantage enumerated as desirable in the statement of the invention and the above description, and while we have, in the present instance, shown and described preferred embodiments thereof which will give in practice satisfactory and reliable results, it is to be understood that the same is susceptible of modification in various particulars without departing from the spirit or scope of the 120 invention or sacrificing any of its advantages.

Having thus described our invention what we claim as new and desire to secure by Letters Patent, is:—

1. The combination of a feed water heater, a meter, an air pipe communicating with the interior of said heater and meter and having a common air outlet branch leading to the atmosphere, a vacuum breaker, a check valve and a throttling valve located in said branch.
2. The combination of a feed water heater, a meter, an air pipe communicating with the interior of said heater and meter and having a common air outlet branch leading to the atmosphere, and an air exhaust device located in said branch and consisting of a vacuum breaker, check valve and a throttling valve having a port through the valve disk thereof.
3. The combination of a feed water heater, a meter, and an air pipe communicating with the interior of said heater and meter and having a common air outlet branch leading to the atmosphere, an air exhaust device located in said branch and consisting of a vacuum breaker, check valve and a throttling valve having a port through the disk thereof, said vacuum breaker, check valve and throttling valve being located in said branch in the order named.
4. The combination with a feed water heater, a gravity flow meter, and an air pipe communicating with the interior of said heater and meter, said pipe having a common air outlet branch leading to the atmosphere, said branch having therein an air exhaust device consisting of a vacuum breaker, a steam valve and a throttling valve having a port through the disk thereof.
5. The combination of a gravity flow meter, an air pipe communicating with the interior thereof and having a branch leading to the atmosphere in which are located a vacuum breaker, a check valve and a throttling valve.
6. The combination of a gravity flow meter, an air pipe communicating with the interior thereof and having a branch leading to the atmosphere in which are located a vacuum breaker, a check valve and a throttling valve having a port in the disk thereof.
